United States Patent Office

Des. 218,378
Patented Aug. 11, 1970

218,378

TENT

Charles R. Gretz, Valdosta, Ga., assignor to Transamerican Development Corporation, Valdosta, Ga., a corporation of Georgia

Filed Sept. 10, 1968, Ser. No. 13,478

Term of patent 14 years

Int. Cl. D21—05

U.S. CL. D88—3

FIG. 1

FIG. 2

FIG. 3

FIG. 4

FIG. 1 is a rear elevational view of a tent showing my new design;

FIG. 2 is a front elevational view thereof;

FIG. 3 is a side elevational view thereof; and

FIG. 4 is a bottom plan view thereof, looking from the bottom upward.

I claim:

The ornamental design for a tent, substantially as shown.
